DANCING TOY

Joseph G. Jeffrey, Halifax, Nova Scotia, Canada, assignor of one-third to R. Byron MacLennan, Brookfield, Nova Scotia, Canada, and one-third to Osborne H. Parsons, Halifax, Nova Scotia, Canada.

Application March 1, 1943, Serial No. 477,539

1 Claim. (Cl. 46—137)

The present invention relates to a dancing toy and, more particularly, a toy actuated by the vibrations imparted manually to a platform or stage.

The main object of the invention resides in the provision of a dancing toy of improved design and performance.

Another important object relates to a toy of the character described, which is conveniently operated and capable of a number of movements and adjustments to suit various purposes.

A further object concerns the provision of a toy which is cheaply constructed, necessitates a minimum of metal and is capable of being quickly assembled from a plurality of easily procurable materials.

Still another object envisages a toy which would be operable at any time without special preparations or set-ups.

Other objects and advantages of the invention will become apparent, or be further pointed out, during the description to follow.

As an example, and for purposes of illustration, a preferred embodiment of the invention is shown in the annexed drawing wherein:

Figure 1 is a perspective view of the toy according to the invention,

Figure 2 is a longitudinal vertical section taken through said toy,

Figure 3 is a plan view of the base portion of the toy,

Figure 4 is a vertical section through the dancers' supporting means showing the back of the dancers,

Figure 5 is a view taken on line 5—5 of Figure 4, and

Figure 6 is a side elevation showing the manner of attaching the dancer to the supporting means.

Referring to the drawing, wherein similar reference characters represent corresponding parts throughout, the letter "B" represents the base of the toy, which base consists of an elongated strip 10 having side enlargements at the rear end thereof for purposes of stability, which enlargements are in the form of ears 11. The strip 10 carries, adjacent the ears 11, a spacing block 12, the purpose of which is to support a table 13 which is thus secured in spaced parallel position with respect to the strip 10 by means of wood screws 14 attaching said table to the block 12.

As shown to advantage in Figures 1 and 2, the table 13 is provided, at the front end, with a circular enlargement 19 representing a dancing platform or stage on which the dancers illustrated are adapted to perform. This stage is per-

forated centrally at 15 to allow the passage of a vertical upright post 16 having a conical foot 17 and extending upwardly a certain distance above the stage 19. As shown in Figure 4, the upright is secured to the strip 10 by means of a wood screw 18 securing the foot 17 to the said strip.

The upper end of the post 16 is adapted to rotatably support a cross arm 20 which is retained in position at right angles to the longitudinal axis of the post by means of a nail 21 inserted in said post. It must be noted at this point that the central aperture through which the nail 21 is inserted is of such diameter that the cross arm 20 will be free to rotate easily around said nail, to be explained later. Finally, the cross arm has rounded ends, as shown in Figure 5, said ends being rabbetted to form a lower stop 22 to the center of which a screw-eye 23 is fixed as depicted clearly in Figures 5 and 6.

The dancing figures shown in Figure 1 are fanciful only and, of course, may be changed to suit personal desires and to represent well-known figures, as the case may be. In general, the dancers may be constituted of a body 25 which is preferably cut from flat sheet material for facilitating construction, to which body arms 26 are loosely pivoted by means of the brads or nails 27. The legs must be articulated, however, and for that purpose must be made in sections 28 loosely pivoted together by means such as the transverse wire 29, the feet 30 being secured at right angles to the lower section 28. The dancers are secured to the cross arm 20 by means of screw eyes 31 threadedly engaged in the body 25 of the dancers, at the back thereof, and the eye of which is linked to the eye of the member 23, so as to form a loose pivoted connection. (See Figures 4, 5 and 6.)

In practice, the height of the dancers above the stage 16 is so adjusted that, at rest, the said stage is in such position that the feet of the dancers rest normally flat on said stage, so that the least vibration imparted to the table has a tendency to flex the legs of the said dancers and cause bouncing of the feet over the stage. Therefore, the rigidity of the table 13 must be such that it is able to rest parallel with the base 10, but sufficiently flexible so as to be readily vibrated by the simple expedient of tapping the finger thereon for the purpose of causing oscillation thereof.

Consequently, the flexibility of the table must be adjusted so that it is relatively easy to cause dancing of the figures, in step with a tune, by tapping slightly the table rhythmically with the

music. The result is a very realistic movement of the dancers which, due to their enlarged feet 39, tap the stage 19 in a very life-like imitation of an actual tap dancer, the movement of the legs being transmitted to the body whereby said dancers effectuate very comical contortions while oscillating in an unpredictable manner around the nail 21 on the cross bar 20.

Although two dancers are shown secured to the cross bar 20, it is obvious that, as suggested by the showing of Figure 2, a single dancer may be used as well, secured to a member pivoted to the top end of the post 16, by means of the nail 21, so as to cause rotation of the single dancer around the upright 16.

From the foregoing description, it will be obvious that the present invention offers unlimited amusement possibilities to young and old alike, especially those who are musically inclined and can rhythmically actuate the table 13 in tune with popular songs or music. Although the general idea of the present dancing toy is not new, nevertheless the specific construction described and illustrated has the advantage over the known toy that it can stand by itself on any surface and, therefore, can be used anywhere and under any circumstances. Furthermore, due to the fact that the table 13 is used solely for oscillating purposes and not, as in other cases, to support the toy itself, it is evident that the natural period of vibration of said table is not affected by the manner of holding it and, as a result, the characteristics of the toy are always the same and can be depended upon to remain fixed from time to time.

Again, the use of a stay or platform for dancing purposes, above the toy holding base, constitutes a more realistic representation of tap dancer, the said platform being secured away

from the attaching screws 14, offering better acoustic properties and performing as a better diaphragm.

Therefore, the present invention is obviously an advance of the art, and it must be understood that various changes as to the shape, size and arrangement of parts may be restored to without departing from the spirit of the invention or the scope of the subjoined claim.

Having thus described my invention, I claim:

In a dancing toy including a base, a narrow elongated vibratory member spacedly secured to one end of the base in parallel relation thereto, an enlarged centrally apertured stage formed at 15 the free end of the member, a vertical post secured to the base and extending upwardly above the stage through the aperture thereof, an horizontal cross bar centrally pivoted to the end of the post for free swinging movement, and an 20 articulated dancing figure freely suspended to each end of the cross bar, a screw eye secured to the back of each figure to constitute the figures suspension means, and a similar eye disposed vertically in the center of a step cut at each end 25 of the cross bar and linked to the back eye of one figure to form the pivot, allowing swinging motion of the figures, said step acting as a stop for the back eye of each figure to limit downward movement thereof with respect to the stage, 30 whereby said figures hang freely by the back to each end of the cross bar in a manner allowing an horizontal swinging movement through an arc of 180° around the suspension point a fixed distance above the stage, vibratory movement of the member by the finger of an operator causing audible contact of the stage with the lower limbs of the figures in tune with the motion imparted to said member.

JOSEPH G. JEFFREY.
